UNITED STATES PATENT OFFICE.

JOSEPH A. COSTELLO, OF CLEVELAND, OHIO, ASSIGNOR TO CLEVELAND CAR SPECIALTY COMPANY, OF CLEVELAND, OHIO, A CORPORATION OF WEST VIRGINIA.

METAL CARLINE FOR CAR-ROOF FRAMES.

1,218,629.

Specification of Letters Patent. Patented Mar. 13, 1917.

Application filed September 25, 1915. Serial No. 52,693.

To all whom it may concern:

Be it known that I, JOSEPH A. COSTELLO, a citizen of the United States of America, residing at Cleveland, in the county of 5 Cuyahoga and State of Ohio, have invented certain new and useful Improvements in Metal Carlines for Car-Roof Frames; and I hereby declare the following to be a full, 10 clear, and exact description of the invention, such as will enable others skilled in the art to which it pertains to make and use the same.

This invention relates to improvements in carlines for car-roof-frames, and pertains 15 more especially to a carline made from a rectangular rolled steel plate or sheet pressed into the shape required to form a trough which is long enough to bridge the space between and to extend across the tops 20 of the side plates of a car-roof-frame and has two laterally and outwardly projecting side flanges arranged at opposite sides respectively of the trough and extending along the top and longitudinally of the 25 trough.

One object of this invention is to have said trough not only capable of conducting any water received thereby to the outer sides of the hereinbefore mentioned side 30 plates, but to have the width of the trough at each end of the trough measure considerably more than the distance apart, along the central portion of the carline, of the longitudinal edges of the hereinbefore mentioned 35 flanges to the end of enabling the trough to be adequately seated on the side plates of a car-roof-frame upon the application of the carline.

Another object is to have said trough not 40 only long enough to render it capable of extending from the outer side of one side plate to the outer side of the other side plate of a car-roof-frame and to have the bottom of the trough terminate in downwardly projecting transverse flanges with 45 which the carline is provided at its ends for overlapping the outer sides of said side plates, but to have the end-portions of the carline so contoured that the hereinbefore 50 mentioned side flanges have their end-portions sloping downwardly toward and extending to the outer extremities of the bottom of the trough and there terminating in the downwardly projecting transverse flanges of the carline so that said end- 55

tions of the side flanges materially extend the seats formed by the bottoms of the end-portions of the trough outwardly beyond the sides of the trough and thereby render the carline capable of seating still more adequately on the side plates to such an extent that any tendency from any cause to laterally tip the carline is effectually opposed. 60

Another object is to render a carline of the type indicated adapted, without any 65 shearing or trimming, to be made from a rectangular rolled steel plate or sheet by pressing the plate or sheet into the shape required to form the carline.

With these objects in view, and to the 70 end of attaining any other advantages hereinafter appearing, this invention consists in certain features of construction and relative arrangement of parts hereinafter described, pointed out in the claims, and illustrated in the accompanying drawings. 75

In said drawings, Figure 1 is a top plan of a carline embodying my invention and shown applied to the side plates of a car-roof-frame. Fig. 2 is a vertical section on line 2—2, Fig. 1. Fig. 3 is an enlarged view of a portion of Fig. 2. Fig. 4 is a vertical section on line 4—4, Fig. 3, looking outwardly. Fig. 5 is a left-hand side elevation relative to Fig. 3. Figs. 3, 4 and 5 are 85 drawn on a larger scale than Figs. 1 and 2.

Referring to Figs. 1 and 2 of said drawings, A and A indicate the two laterally spaced horizontally arranged parallel side plates of a car-roof-frame. Each side plate 90 A is shown consisting of a metal bar and provided at the top thereof with a laterally and inwardly projecting substantially horizontally arranged flange a which extends longitudinally of said side plate, and said 95 side plate is shown provided at the bottom with a laterally and outwardly projecting flange 6. The side plates A are shown connected together by my improved metal carline which comprises a trough B which 100 bridges the space between and is mounted on the top flanges a of the side plates, and said trough extends across said flanges. The car line is provided with two vertically downwardly projecting flanges 7 and 7 105 which are arranged at opposite ends respectively and transversely of the carline and shown overlapping the outer side of opposite side plates A and A respectively. Each transverse flange 7 therefore con- 110

stitutes a lateral abutment for the outer side of the adjacent side plate. The trough B extends to the outer sides of the flanges 7 so that any water received by the trough is conducted to the outer sides of said flanges. 5 To cause the bottom of the trough to be adequately seated on the side plates each end-portion of the trough and the bottom 8 of said end-portion of the trough (see Fig. 1) 10 is gradually enlarged in width from a point shown spaced inwardly from the adjacent side plate in the direction of the outer side of said side plate and to the adjacent transverse flange 7 of the carline and consequently to the outer extremity of said end-portion of the trough. The bottom 8 of each end-portion of the trough is horizontal and shown secured to the adjacent side plate by rivets 12. 15 The trough is provided at the top and externally with two laterally and outwardly projecting side flanges b and b arranged at opposite sides respectively of the trough and extending longitudinally and from end to end of the trough. The bottom of the trough extends substantially horizontally inwardly, as at 13, from the bottom 8 of each gradually widened end-portion of the trough (see Figs. 1 and 2) to a point 14 approximately 20 central between said end-portion and a point 15 approximately central between the ends of the carline, and upwardly toward the last-mentioned point, and the trough is substantially uniform in depth between said points, 25 but gradually reduced in depth from the first-mentioned of said points in the direction of said end-portion of the bottom of the trough and more conspicuously but gradually reduced in depth at the outer end of said end-portion of said bottom toward and to the outer extremity of said end-portion of said bottom, and each side flange b is preferably gradually enlarged in width (see Fig. 30 1) from adjacent the first-mentioned of said points toward and to said end-portion of the bottom of the trough and thence reduced in width toward and to the outer extremity of said end-portion of said bottom, as shown in Figs. 1 and 5. 35 Each end-portion of each side flange b is shown sloping quite steeply, as at 16, over the adjacent side plate toward and to the outer side of said side plate. Each transverse flange 7 of the carline extends to the 40 longitudinal edges of the side flanges b. Each sloping end-portion 16 of each side flange b terminates in the adjacent downwardly projecting transverse flange 7 of the carline, and hence said portion 16 of each side flange has its lower extremity arranged in line transversely of the trough with the adjacent extremity of the bottom of the trough, and said portion of said side flange terminates therefore at said extremity 45 of said bottom. It will be observed that the

bottom of the trough is widest at the lower extremities of the sloping end-portions 16 of the side flanges b, and that the bottom 8 of each gradually widened end-portion of the trough is not only widest at the outer 70 extremity of said end-portion of the trough, but that the width of said bottom of said end-portion of the trough measures at said extremity considerably more than the distance apart, along the central portion of the 75 carline, of the longitudinal edges of the side flanges b.

A carline embodying the invention hereinbefore described has not only great strength and stiffness in its end-portions, but is inexpensively formed, without waste, from a rolled steel plate or sheet of minimum dimensions, and has said end-portions so contoured that the carline is capable of seating on the side plates of a car-roof-frame in such 80 a manner and to such an extent as to effectually oppose any tendency from any cause to tip the carline laterally.

It will be observed also that by the gradual enlargement in the width of the flanges 90 of the carline from points spaced inwardly from the gradually widened end-portions of the trough toward and to said end-portions of the trough, and by said flanges being widest at the inner ends of the said end-portions of the trough, the carline has adequate strength adjacent the inner ends of said end-portions of the trough. I would also remark that it is not unimportant only to have each end-portion of each of the said 100 flanges of the carline slope downwardly toward and terminate at the outer extremity of the adjacent end-portions of the bottom of the trough, but that the width of said bottom at the lower ends of said end-portions of said flanges of the carline measures more than the distance between the longitudinal edges of said flanges along the central portion of the trough and that the enlarged end-portions of said bottom are wide 105 enough over the laterally and inwardly projecting flanges of the metal side plates to permit the application of the two rivets shown and required to efficiently secure said bottom to said flanges of the side plates, 110 without necessitating the use of more expensive devices, such for instance, as bolts and nuts, for securing the trough at its sides to the side plates.

What I claim is:—

1. A metal carline comprising a trough having the end-portions thereof gradually enlarged in width toward their outer extremities, which trough is provided at the top with laterally and outwardly projecting 12 flanges extending longitudinally and from end to end of the trough, each end-portion of each of said flanges sloping toward the outer extremity of the adjacent end-portion of the bottom of the trough, the said bottom 13

- being substantially horizontal from the outer extremity of each gradually widened end-portion of the trough to a point spaced inwardly from said portion of the trough 5 and thence extending upwardly toward a point central between the ends of the car-line, the aforesaid flanges being substantially uniform in width between said points and there being a gradual enlargement in 10 the width of said flanges from the first-mentioned point toward and to the adjacent gradually widened end-portion of the trough, and said flanges being widest at the inner ends of the gradually widened end- 15 portions of the trough.
2. The combination, with the two laterally spaced metal side plates of a car-roof-frame, said side plates being provided at the top with laterally and inwardly projecting flanges extending longitudinally of said side plates, of a metal carline comprising a trough which bridges the space between the side plates and extends over the aforesaid flange and has the bottom of each end-portion thereof enlarged in width toward the 20 outer extremity of said end-portion, said trough being provided at the top and externally with laterally and outwardly projecting flanges extending longitudinally and from end to end of the trough, each end-portion of each said flanges of the carline sloping downwardly toward and terminating at the outer extremity of the adjacent end-portion of the bottom of the trough, the width of said bottom at the lower ends 30 of said end-portions of said flanges of the carline measuring more than the distance between the longitudinal edges of said flanges along the central portion of the trough, and the enlarged end-portions of 35 said bottom being riveted to the aforesaid flanges of the side plates.
- 25 In testimony whereof, I sign the foregoing specification, in the presence of two witnesses.

JOSEPH A. COSTELLO.
